US0D1077823S

(12) **United States Design Patent** (10) Patent No.: **US D1,077,823 S**
(45) Date of Patent: ** Jun. 3, 2025

(54) **DISPLAY SCREEN WITH GRAPHICAL USER INTERFACE**

(71) Applicant: **DELTA ELECTRONICS, INC.**,
Taoyuan (TW)

(72) Inventors: **Ku-Yun Lee**, Taoyuan (TW); **Yen-Yu Chen**, Taoyuan (TW); **Shih-Han Chan**, Taoyuan (TW)

(73) Assignee: **DELTA ELECTRONICS, INC.**,
Taoyuan (TW)

(**) Term: **15 Years**

(21) Appl. No.: **29/748,712**

(22) Filed: **Aug. 31, 2020**

Related U.S. Application Data

(62) Division of application No. 29/663,016, filed on Sep. 11, 2018, now Pat. No. Des. 923,653.

(57) **CLAIM**

The ornamental design for a display screen with graphical user interface as shown and described.

DESCRIPTION

The single FIGURE is a front view of a display screen with graphical user interface showing our new design.

The broken lines illustrate portions of the display screen with graphical user interface that form no part of the claimed design.

1 Claim, 1 Drawing Sheet
